J. GESCHKE

MAGNET WHEEL

Filed March 31, 1926

Fig. 1.

Fig. 2.

Inventor:
Johannes Geschke,
by Alexander S. Zentz
His Attorney.

UNITED STATES PATENT OFFICE.

JOHANNES GESCHKE, OF BERLIN, GERMANY, ASSIGNOR TO GENERAL ELECTRIC COMPANY, A CORPORATION OF NEW YORK.

MAGNET WHEEL.

Application filed March 31, 1926, Serial No. 98,787, and in Germany April 7, 1925.

My invention relates to magnet wheels for dynamo-electric machines and particularly to such wheels which are of large size and have segmentally divided rims. An object 5 of my invention is the provision of a magnet wheel of this type having improved means for securing the rim segments so as better to enable the wheel to withstand the great stresses to which it is subjected.

10 My invention will be better understood from the following description taken in connection with the accompanying drawing, and its scope will be pointed out in the appended claims.

15 Referring to the drawing, Fig. 1 is a fragmentary side elevation of a magnet wheel embodying my invention and Fig. 2 is a section on the line 2—2 of Fig. 1.

The magnet wheel which I have illustrated is of very large size and is accordingly built up of separate parts. The hub 1 which may be made in a single piece or in two or more pieces has the central under-cut flange portion 2 to which are secured, as for example by bolts 3, pairs of axially displaced spokes or arms 4. The rim of the wheel is formed by two series of rim segments 5 which are secured as by the bolts 6 to the outer side faces of the spokes. Suitable flanged spacing segments 7 are shown between the spokes at their outer ends.

As shown in Fig. 1 the rim segments 5 extend each from a point opposite the center line of one spoke to a point opposite the center line of the second spoke therefrom, making butt joints with one another with the line of division extending radially. The segments lie against the side faces of the spokes and have extended areas of contact therewith which permits the use of a sufficient number of bolts to make the necessary firm connection between the spokes and the rim segments. This area of contact between the spokes and the segments is moreover increased by making the spoke ends of greater width circumferentially than the body portions thereof. At the ends of the segments where additional securing means is desirable the segments are made with a

greater width radially, thus facilitating the 50 use of additional securing bolts. The rim comprising the segments 5 and the spacer 7 is shown having a cylindrical periphery to which field magnets or the like may be fixed by any suitable means. 55

What I claim as new and desire to secure by Letters Patent of the United States is:

1. A magnet wheel comprising a series of spokes having their ends widened to form a 60 substantially continuous peripheral web, and a plurality of rim segments secured against the sides of the spokes, the segments being arranged with their ends substantially opposite the center lines of certain of the 65 spokes.

2. A magnet wheel comprising a hub, a series of spokes secured thereto having their ends widened to form a substantially continuous peripheral web, a plurality of rim 70 segments having portions overlying the sides of the spokes, and means for securing the segments to the spokes, the respective segments being constructed to form butt joints with each other at points arranged substantially opposite the center lines of certain of the 75 spokes.

3. A magnet wheel comprising a hub, a series of spokes having their outer ends circumferentially extended to form a substantially continuous peripheral web, a rim comprising a plurality of segments having joints arranged substantially opposite the center lines of certain of the spokes and means for securing the segments to the side faces of the 85 spokes at the circumferentially extended portions thereof.

4. A magnet wheel comprising a hub, a series of spokes secured thereto, a rim comprising a plurality of segments making butt 90 joints with one another and arranged substantially opposite the center lines of certain of the spokes, said segments having widened end portions, and means passing through the widened end portions of the segments 95 and through intermediate portions thereof for securing the segments against the sides of the spokes.

5. A magnet wheel comprising a hub, pairs of axially displaced spokes secured thereto, a space block between the outer ends of said spokes having flanges, two series of 5 rim segments engaging respectively the outer side faces of the spokes of each pair and said space block, securing bolts passing through the rim segments, the space blocks

and the end portions of the spokes, the adjacent rim segments making butt joints with 10 each other on lines lying substantially opposite the center lines of certain spokes.

In witness whereof, I have hereunto set my hand this 16th day of March, 1926.

JOHANNES GESCHKE.
